(57) **CLAIM**

The ornamental design for a laptop case, as shown and described.

DESCRIPTION

FIG. 1 is a front, left, top perspective view of a laptop case, showing my new design;

FIG. 2 is a front, left, top perspective view of the first piece of a laptop case, showing my new design;

FIG. 3 is a rear, right, bottom perspective view thereof;

FIG. 4 is a front elevational view of the enlarged scale thereof;

FIG. 5 is a rear elevational view of the enlarged scale thereof;

FIG. 6 is a left side view of the enlarged scale thereof;

FIG. 7 is a right side view of the enlarged scale thereof;

FIG. 8 is a top plan view of the enlarged scale thereof;

FIG. 9 is a bottom plan view of the enlarged scale thereof;

FIG. 10 is an enlarged view of detail 10 in FIG. 2;

FIG. 11 is an enlarged view of detail 11 in FIG. 3;

FIG. 12 is an enlarged view of detail 12 in FIG. 4;

FIG. 13 is an enlarged view of detail 13 in FIG. 5;

FIG. 14 is an enlarged view of detail 14 in FIG. 6;

FIG. 15 is an enlarged view of detail 15 in FIG. 8;

FIG. 16 is a front, left, top perspective view of the second piece of a laptop case, showing my new design;

FIG. 17 is a rear, right, bottom perspective view thereof;

FIG. 18 is a front elevational view of the enlarged scale thereof;

FIG. 19 is a rear elevational view of the enlarged scale thereof;

FIG. 20 is a left side view of the enlarged scale thereof;

FIG. 21 is a right side view of the enlarged scale thereof;

FIG. 22 is a top plan view of the enlarged scale thereof; and,

FIG. 23 is a bottom plan view of the enlarged scale thereof.

The dashed broken lines in the figures illustrate portions of the laptop case that form no part of the claimed design.

The dash-dot-dash broken lines are for notating enlarged views and form no part of the claimed design.

1 Claim, 20 Drawing Sheets
